UNITED STATES PATENT OFFICE.

CHARLES FRANCIS JENKINS, OF WASHINGTON, DISTRICT OF COLUMBIA.

MULTIPLE LIGHT-CELL TRANSMITTER.

Application filed April 1, 1925. Serial No. 19,811.

This invention relates to apparatus employed in the broadcasting of motion pictures and the like, and has for its main object means for increasing the efficiency 5 of the light-sensitive cells used in such apparatus.

In the analysis of an active scene or picture for visual radio broadcasting, the scene or picture is, in imagination, though not actually, divided into little squares of equal number each way in a square picture. For example, in a ten inch square picture with an imaginary division of 50 lines per inch each way there would be 250,000 little 15 squares. To make up a picture over this surface the squares would be divided again, the increased number of sub-divisions being a varying quantity as the moving scene or picture changed.

Obviously the light sensitive cell which analyzes this scene must respond to the light changes just described, and must recover its initial condition just as quickly. A cell which has a lag, that is, does not recover 20 sensitivity as quickly as it initially acts, is no more useful than a sluggish-acting cell. And this has been one of the serious obstacles to a more rapid development of radio movies; for while a single cell will respond over a considerable range of frequencies, the lag in recovery of the cell makes the high-frequency change in current very minute, so small at higher frequencies that it is almost impossible to amplify it because 25 it is overridden by tube noises.

Several different types of light cells respond fast enough, but as no cell known to applicant is without recovery lag, the following method and mechanism has been developed to avoid the results of lag in recovering sensitivity.

With this and other objects in view the invention consists in the novel details of assembly of the various devices employed, hereinafter disclosed, and particularly pointed out in the claims.

In the drawings, Fig. 1 is a schematic illustration of the invention, and Figs. 2 and 3 detail parts. In the figures A is a 50 source of light located in front of an aper-

ture B in the mask C. In alignment with the light source and the aperture is a small mirror D mounted upon a rotatable shaft E at a 45° angle to the axis of a shaft. Upon the opposite end of the shaft is a single contact disc F which in rotation shifts the current of battery G alternately to light cell H and H¹, H², and H³; and through each in succession to the tube K, the first tube 55 of an amplifier circuit.

The sensitivity of most cells is practically instantaneous and with the recovery time known, it is easy to determine the number of cells required to take care of the entire lag of each cell. That is, whether two, 60 three, four, or more cells are desirable.

It is believed that, the object sought and the method of obtaining it understood, the operation of the apparatus will be readily apparent. That is, when light from source A falls on the mirror D it will be reflected to one of the cells, H², for example, thereafter to impinge on the other cells, H³, H⁴ and H¹ in succession.

As the light is cut off each cell for three-fourths of the total time, each cell has a corresponding time in which to recover its original sensitivity, and, therefore, the resultant phase amplitude on the amplifier is maximum.

It is also quite well understood that each cell passes but a very small current, and if the arrangement takes off of each cell its peak current the maximum total current available is materially increased.

Obviously, it is not necessary to limit the mechanism to that shown herein, for other schemes may be employed for connecting the cells to the outlet circuit.

What I claim, is—

1. In apparatus of the class described, the combination of a plurality of fixedly-located light-sensitive cells, a light source, an aperture of approximately equal dimensions in right angle directions and located between the light source and the cells, and a continuously rotating mirror for directing said light to each sensitive cell in succession.

2. In apparatus of the class described, the combination of a plurality of fixedly-located

light-sensitive cells, a light source, an aperture between the light source and the cells, and a continuously rotating mirror for directing said light to each said cells in succession.

3. In apparatus of the class described, the combination of a plurality of fixedly-located

light-sensitive cells, a light source, and a continuously rotating mirror for directing said light to each said cells in succession.

10

In testimony whereof I have affixed my signature.

CHARLES FRANCIS JENKINS.
